UNITED STATES PATENT OFFICE.

ROY E. JONES, OF STORRS, CONNECTICUT.

WATER FOUNTAIN FOR CHICKENS.

Application filed March 7, 1922. Serial No. 541,651.

To all whom it may concern:

Be it known that ROY E. JONES, a citizen of the United States, residing at Storrs, in the county of Tolland and State of Connecticut, has invented certain new and useful Improvements in Water Fountains for Chickens, of which the following is a specification.

This invention relates to a water fountain for chickens. Among the objects of the invention are the provision of an appliance of the character set forth which is simple in construction, capable of ready and easy manufacture, the water of which will not freeze in cold weather, and by which the perching or roosting of chickens on the fountain is prevented with certainty. Another object is the provision of effective means by which the fountain can be automatically filled with water.

In the drawing accompanying and forming part of the present specification I have shown in detail one of the several forms of embodiment of the invention, which to enable those skilled in the art to practice the same will be set forth fully in the following description. Obviously I am not restricted to this showing. I may depart therefrom in a number of respects within the scope of the invention defined by the claims following said description.

Referring to said drawing:

Fig. 1 is an elevation, partly in vertical section, of a fountain involving the invention.

Fig. 2 is a side elevation of the same.

Fig. 3 is a detail of valve mechanism.

Like characters refer to like parts throughout the several views.

The appliance involves in its makeup, a body portion such as 2 and which as represented is in the form of a more or less cylindrical shell open in the upper and the lower sides and the lower side of which is intended to rest upon the surface of the ground.

This shell 2 constitutes as illustrated, a suitable receiver for the water tank or pan 3 which is also usually circular in form but somewhat shallower than the body portion 2 in which it generally fits, the marginal portion of the tank or pan 3 fitting the body 2 and it being on a somewhat downward taper, so that it can be readily inserted in the body or vessel 2 when the parts are to be in working condition. When this relation is present the bead 4 on the outer margin of the tank

or pan rests upon the upper edge of the body 2.

The water for the tank or pan 3, can be conducted thereinto in any proper manner, the supply-pipe 5 being shown for the purpose. This supply pipe is extended into the bottom of the tank or pan 3 in some water-tight manner. In the upper portion of the pipe 5 is situated a tubular seating member 6, the upper edge of which is practically flush with the upper end of the pipe. Said pipe is provided at its upper end with lugs 7 and 8, the lever 9 being pivoted at its outer end to the lug 7. This lever 9 constitutes a carrier for a valve 10 which may consist of a disk of rubber attached suitably to the under side of the lever 9.

The tank or pan receives within it the float 11 fastened at the free end of the somewhat bent lever 12 which is fulcrumed near its forward end to the lug 8 in such manner that the toe of the lever may engage the outer or free end of the lever 9. When the valve 10 is open water can flow into the tank or pan 3 from the pipe 5 thus causing the float 11 to rise that portion of the lever to the right of its fulcrum being correspondingly moved so that the toe portion of the lever 12 will be thrust downward and engage the upper free portion of the lever 9 and close the valve 10, the valve being fully closed against its seat when the level of the water is at the predetermined level which is approximately about that indicated by dotted lines in Fig. 1.

There may project through the bottom of the tank or pan 3, the waste or overflow pipe 13 which is extended through the bottom of the tank in some water-tight manner. This overflow pipe may have one or more overflow openings as 14 which are in the form of properly-sized perforations so that in the event that the valve mentioned sticks, there can be no overflow of the tank, for before this can occur the water will escape to the waste or overflow pipe 13 by the way of these openings 14.

In conjunction with the tank or pan 3, I provide what might be considered a guard which as represented is in the form of a hollow cone 15 having depending from its lower end the angularly-disposed legs 16 which are adapted to rest on the bottom of the tank or pan near the wall portion thereof, the angularity of these legs agrees substantially with that of the cone. Said cone 15 may be

provided exteriorly with a handle 17 by which it can be easily manipulated. The chickens can readily reach the water in the tank or pan 3 through the spaces or intervals between the legs 16.

The freezing of the water in the tank or pan 3 is prevented in some convenient manner as by a heater of some suitable kind, the lamp 18 being shown for the purpose. This lamp may use any proper substance, for instance, ordinary kerosene, and when the wick of the burner is lighted the heat will radiate against the bottom of the tank or pan 3 and thus prevent possibility of the water therein freezing.

To introduce or remove the heater or lamp 18, the body or vessel 2 may be furnished with an opening provided with a door 19. The door may have a handle 20 to render easy its opening or closing. It may also have therein one or more openings 21 for the admission of atmospheric air to promote the proper combustion of the flame of the burner.

25 What I claim is:—

1. An appliance of the character described, comprising a shell, a pan within the shell, to contain water, the marginal portion of the pan resting upon the upper edge 30 of the shell, a water-pipe extending into the pan, a valve for the water-pipe, a float-operated lever for actuating the valve, and a cone provided on its underside with straight legs the angle of which agrees approximately 35 with that of the body of the cone and spaced apart, said legs resting on the bottom of the pan, the openings between said legs providing access by the chickens to the water contained within the cone.

40 2. An appliance of the character de-

scribed, comprising a shell, a pan within the shell, to contain water the marginal portion of the pan resting upon the upper edge of the shell, a water-pipe extending into the pan, a valve for the water-pipe, a float operated lever for actuating the valve, a cone provided on its under side with straight legs, the angle of which agrees approximately with that of the cone, spaced apart and resting upon the bottom of the pan and against the wall thereof to thus steady the cone, and an overflow pipe extending into the pan through the bottom thereof the overflow pipe having an escape opening.

3. An appliance of the character described comprising a shell, a downwardly tapered pan within the shell, to contain water, the marginal portion of the pan resting upon the upper edge of the vessel said pan closely fitting the vessel, a water-pipe 60 extending into the pan, a valve for the water-pipe, a float-operated lever for actuating the valve, a cone provided on its under side with straight legs the angle of which agrees approximately with that of the cone, 65 spaced apart and resting upon the bottom of the cone, and against the wall thereof to thus steady the pan, the cone having exteriorly thereof a handle, and an overflow pipe extending into the pan through the bottom thereof the overflow-pipe having an escape opening above the bottom of the pan, the vessel being provided with a door for an opening therein, the door having air openings.

In testimony whereof I affix my signature.
ROY E. JONES.

In presence of—
HAZEL BECK,
HEATH SUTHERLAND.
